(57) **CLAIM**

The ornamental design for a luminaire, as shown and described.

DESCRIPTION

FIG. 1 is a perspective view of a first embodiment of a luminaire, showing our new design.

FIG. 2 is a bottom view thereof;

FIG. 3 is a top view thereof;

FIG. 4 is a side view thereof; and,

FIG. 5 is an end view thereof.

The drawing features shown in broken lines are shown for illustrative purposes only and do not form part of the design.
